CASE SHIFT MECHANISM

Filed Jan. 10, 1925

Patented Aug. 23, 1927.

1,640,127

UNITED STATES PATENT OFFICE.

JAMES F. KOCA, OF WOODSTOCK, ILLINOIS, ASSIGNOR TO WOODSTOCK TYPEWRITER COMPANY, OF WOODSTOCK, ILLINOIS, A CORPORATION OF ILLINOIS.

CASE-SHIFT MECHANISM.

Application filed January 10, 1925. Serial No. 1,530.

This invention relates to case shift mechanism for typewriters and is especially useful in connection with power driven typewriters such as that shown in the application of Otto A. Hokanson, Serial No. 732, 615, filed August 18, 1924.

The invention has for one of its objects the provision of case shift mechanism which will permit the shiftable member to be moved by a power actuated drive and will retain the member in its shifted position so long as the shift key is held depressed.

A further object is to provide case shift mechanism which shall be of improved construction and operation.

The invention is exemplified in the combination and arrangement of parts shown in the accompanying drawing and described in the following specification, and it is more particularly pointed out in the appended claims.

In the drawing—

Fig. 1 is a vertical sectional view of a portion of a typewriter having one embodiment 25 of the present invention applied thereto; and

Fig. 2 is a fragmentary top plan view of a detail of construction.

The numeral 10 designates a typewriter frame having a power driven toothed cylinder 11 journaled therein. A shift lever 12 is pivoted at 13 and carries a contact device 14 arranged to engage a lug 15 on an actuator 16. The actuator 16 is pivotally connected at 17 to a rocker 18 pivotally mounted at 19 on a cross-bar 20. When the lever 12 is depressed the actuator 16 will be moving downwardly to bring a contact tooth 21 into engagement with the power drive 11. This will move the actuator 16 forwardly until its inclined surface 22 contacts with an adjustable screw 23 mounted on a cross-bar 24. The contact between the cam face 22 and the screw 23 will disengage 45 the tooth 21 from the power drive 11. The spring 25 will then return the actuator 16 to its initial position.

A link 26 is pivotally connected at 27 to the rocker 18 and has its rear end pivotally connected at 28 to an arm 29 formed rigid with the shift frame 30. The shift frame 30 is pivotally mounted at 31 on the typewriter frame 10. An adjustable sliding connection comprising a screw 32 and slots 33 permits return movement of the rocker

18 while the rear end of the link 26 is retained in its forward position. Forward movement of the rocker will rotate the shift frame 30 in a clockwise direction to shift the platen for upper case writing. Means is provided for retaining the platen in its upper position so long as the shift lever 12 is depressed. This retaining mechanism comprises a stop 34 mounted on the shift frame 30 and a detent 35 having a shoulder 36 thereon for engaging the stop 34. The detent 35 is pivoted at 37 and is provided with a spring 38 for normally urging the detent upwardly. When the shift frame is actuated by the power mechanism the shoulder 36 will snap into position behind the stop 34 and retain the platen in its uppermost position.

The forward end of the detent 35 in front of the shoulder 36 is slotted to receive a releasing dog 39 pivotally mounted at 40 in the slotted end of the detent. The dog 39 is provided with a downwardly extending arm 41 which is pivoted at 42 to a link 43. The link 43 is pivotally connected at 44 to an arm 45 formed integral with the shift lever 12 and extending upwardly therefrom. When the key lever is depressed the arm 45 moves forwardly, thus rotating the release dog 39 in a clockwise direction so as to bring the upper edge of the dog flush with the upper face of the bifurcated portion of the detent 35. This permits the shoulder 36 to engage the stop 34 and so long as the shift lever is depressed the shoulder 36 will hold the shift frame 30 in its upper position irrespective of the action of the power driven mechanism. When the shift lever is released, however, the spring 46 will raise the shift lever and move the arm 45 rearwardly which will rotate the release dog 39 in a counter-clockwise direction and force the shoulder 36 out of engagement with the stop 34. This will permit the platen to move downwardly into its lower case position. In this way mechanism is provided by means of which the power for shifting the typewriter parts is furnished by the power drive 11 but the parts will remain in their shifted position so long as the key is held depressed.

I claim:

1. Typewriter mechanism comprising a pivoted shift frame, a stop mounted on said shift frame, a spring actuated detent having a shoulder for engaging said stop, a

release dog movably connected on said de-
tent adjacent said shoulder for engaging
said stop to disconnect said detent from
said stop, a shift lever, and means for con-
necting said shift lever with said dog.

2. Typewriter mechanism comprising a
shift frame, a power drive, an actuator for
said shift frame, a shift lever for connect-
ing said actuator and power drive, a link
10 for connecting said actuator and shift frame
arranged to permit return movement of
said actuator independently of said shift
frame, a detent for automatically retaining
said shift frame in its shifted position, and
15 means controlled by said shift lever for
releasing said detent.

3. In a typewriter, a pivotally mounted
shift frame having a stop member mounted
thereon, a detent slidably engaging said
20 stop member and having a shoulder for en-
gaging said stop member to retain said
frame in shifted position, a shift key lever,
a releasing dog pivotally mounted on said
detent adjacent said shoulder and in position
to engage said stop member, and means
connecting said dog with said shift key
lever to force said detent out of engage-
ment with said stop member when said
shift key lever is released.

30 4. In a typewriter, a pivotally mounted
shift frame, a shift key lever, a stop mem-
ber carried by said shift frame, a detent
having a shoulder thereon for engaging

said stop member to retain said shift frame
in shifted position, a spring for urging 35
said shoulder into holding relation with
said stop member when said frame is shift-
ed, a bell crank lever mounted on said de-
tent adjacent said shoulder and constitut-
ing a release dog for said detent, an arm 40
extending upwardly from said shift key
lever, and a link connecting said arm and
bell crank lever to rotate said bell crank
lever and release said detent when said shift
lever is released.

45 5. A typewriter comprising a power
drive, a shift frame, an actuator for con-
necting said shift frame with said power
drive to effect case shift movement, a case
shift lever for moving said actuator into
50 operative relation with said power drive,
means for automatically disconnecting said
actuator from said power drive after a case
shift movement is effected, a spring actuated
detent having a shoulder thereon for re-
taining said shift frame in its shifted posi-
tion, a release dog pivotally mounted on
55 said detent adjacent said shoulder, an arm
projecting upwardly from said case shift
lever, and a link connecting said arm and
release dog to release said detent when said
case shift lever is released.

In testimony whereof I have signed my
name to this specification on this 7th day
of January, A. D. 1925.

JAMES F. KOCA.
